United States Patent Office.

BENJAMIN ANYAN, OF FITCHVILLE, OHIO.

Letters Patent No. 75,826, dated March 24, 1868.

IMPROVEMENT IN CULTIVATORS.

The Schedule referred to in these Letters Patent and making part of the same.

TO ALL WHOM IT MAY CONCERN:

Be it known that I, BENJAMIN ANYAN, of Fitchville, in the county of Huron, and State of Ohio, have invented a new and improved Cultivator; and I do hereby declare that the following is a full, clear, and exact description thereof, which will enable those skilled in the art to make and use the same, reference being had to the accompanying drawings, forming part of this specification.

This invention relates to a new and improved cultivator for cultivating plants grown in hills or drills, and it consists in a novel construction of the same, as hereinafter fully shown and described, whereby the device may be applied to the front axle of any ordinary farm-wagon. In the accompanying sheet of drawings—

Figure 1 is a side sectional view of my invention, taken in the line $z z$, fig. 3.

Figure 2, a detached plan or top view of the front part of the running-gear of an ordinary farm-wagon.

Figure 3, a plan or top view of the device complete.

Similar letters of reference indicate corresponding parts.

A represents the front axle of an ordinary farm-wagon, B the wheels, and C the draught-pole, secured by a bolt, between hounds D D, as usual, (see fig. 2.) E is the bolster, attached to the axle A, in the ordinary way, and F is a driver's seat, having its supports attached to the bolster, and a cross-bar, a^x , secured to a bar, b^x , between the hounds. In adapting the above parts to a cultivator, the draught-pole C is detached, and another, G, used instead. This pole G is attached by a pivot-bolt, a , to the front ends of two supplemental hounds $b b$, which are secured by a bolt, c , to the front ends of the hounds proper, D D. By this arrangement the draught-pole is allowed an up-and-down and a lateral play or movement, the latter being for the purpose of guiding the machine, turning it to the right or left quickly, and with facility, which is done by the action of the feet of the driver against a notched segment, E, attached to the rear of pole G. H H represent the front shovels of the cultivator, which are attached to standards I I, the upper ends of the latter being fitted on the bolt c . These standards are braced by chains $d d$, which are connected to a hook, e , at the front ends of the hounds $b b$. There are two pairs of rear shovels, J J', the standards, K, of which are pivoted in bars L L, the latter being bolted to the cross-bar a^x , and another cross-bar, c^x , of the bar b^x . These standards K are braced by chains d^x , the front ends of which are connected to the axle A, as shown clearly in fig. 1. M is a guard, composed of a sheet-metal plate, bent or doubled, and perforated at each side. This guard is suspended at its front end from the front ends of the supplemental hounds $b b$, and suspended at its rear end from the cross-bar c^x . The guard prevents clods of earth being cast upon the plants by the shovels.

It will be seen from the above description that the parts of the cultivator may, without any difficulty whatever, be applied to the front running-gear of any ordinary farm-wagon, and a cultivator thereby attained by every farmer at a very small expense, and one which will operate equally as well and answer all the purposes of more pretentious machines.

I claim as new, and desire to secure by Letters Patent—

1. The supplemental hounds $b b$, with the draught-pole G attached, and both said parts attached to the hounds proper, D D, as shown, when said parts are applied to or used in connection with the front running-gear of an ordinary farm-wagon, for the purpose specified.

2. The attaching of the standards I I, of the front shovels H, to the supplemental hounds $b b$, and the attaching of the standards K, of the rear shovels J J', to the bars L L, connected to the hounds proper D D, substantially as and for the purpose set forth.

The above specification of my invention, signed by me, this 6th day of January, 1868.

BENJAMIN ANYAN.
